United States Patent Office

Des. 206,223
Patented Nov. 15, 1966

206,223

CHILD'S HIGH CHAIR OR THE LIKE

Albert T. Haley, 650 Michigan Ave., Apt. 14,
Miami, Fla.

Filed Sept. 3, 1965, Ser. No. 86,833

Term of patent 7 years

(Cl. D15—1)

The back of the high chair is plain.

I claim:

The ornamental design for a child's high chair or the like, substantially as shown and described.
